UNITED STATES PATENT OFFICE

CHARLES DRIEST, OF MARLBORO, NEW JERSEY

FUSE AND SWITCH BOX

Application filed March 9, 1928. Serial No. 345,689.

This invention relates to combination switch and fuse boxes for controlling electric circuits and principally the feed circuit to electric meters; and the object of the invention is to provide a box of the class specified which is so constructed as to prevent unauthorized parties from tapping into the electrical feed lines entering a building of any kind or class and which is provided with means for indicating interference with or an attempt to use the current in an unauthorized way; a further object being to provide means externally of the box for moving the switch into open and closed circuit positions with means for retaining the switch in the closed circuit position; a further object being to provide means for quickly releasing said switch operating means to permit the quick movement of the switch arm in the operation of breaking the circuit; a further object being to arrange within the box or casing an adjustable fuse supporting member with means thereon for supporting a plurality of independent fuses, and means arranged externally of the box for actuating said member to move the respective fuses into operative position to complete the circuit through the separate wires passed into and outwardly through the box, which circuit is controlled by said switch; a further object being to provide means whereby a new fuse may be replaced for an old or burned out one without interfering with the seal or closure for the box or casing; a still further object being to provide means for preventing the movement of the fuse supporting members when the switch is in operative or closed circuit position; and with these and other objects in view, the invention consists in a device of the class and for the purpose specified which is simple in construction, efficient in use and which is constructed as hereinafter described and claimed.

The invention is fully disclosed in the following specification of which the accompanying drawings form a part, in which the separate parts of my improvement are designated by suitable reference characters in each of the views, and in which:—

Fig. 1 is a front view of a box or case made according to my invention.

Fig. 2 is a front view of the box with the cover removed.

Fig. 3 is a cross section of the box on the line 3—3 of Fig. 1.

Fig. 4 is a section on the line 4—4 of Fig. 2.

Fig. 5 is a sectional detail view of a part of the construction shown in Fig. 3; and,

Fig. 6 is a partial section on the line 6—6 of Fig. 3.

In carrying my invention into effect, I provide a box or casing comprising a box member 10 consisting of back and side wall members, the side wall members having a plurality of knock out plugs 10a to permit the passage of wires into and out of the box or the coupling of tubes therewith, through which the wires pass, two of the knock outs being removed, one on the top wall and the other on the bottom wall. In the drawings, I have shown pipes 11 and 12 coupled with the top and bottom walls respectively. It is also preferred that the back wall be provided adjacent the top of the box with key-hole apertures 13 by means of which the box may be detachably secured to a suitable support, by screws or other devices, the heads of which are arranged within the box as will be apparent.

I also provide a cover 14, the walls of which overlie the side walls of the box 10 as clearly seen in Fig. 3. The cover is provided adjacent the upper end of the box with a transparent panel 15, and approximately centrally thereof with a depressed portion 14a which is apertured to receive a shaft as later described. At opposite sides of the lower end portion of the cover are two comparatively large apertures 14b which are normally closed by arc-shaped or hood-like cover plates 16 hinged to the cover as seen at 16a.

The cover is secured in position by two screws 17 and 18, the former cooperating with a rod-like support 17a secured to the bottom wall of the box, whereas the screw 18 passes through a bushing 18a secured to the cover 14, note Fig. 5, and is normally locked to the bushing by the wire of a seal 19 which passes through apertures in the shank of the

screw and said bushing. The inner or threaded end of the screw engages a rod 20 secured to the back wall of the box 10, and slidably mounted on said rod is a sleeve 20a normally held in an outward position by a spring 21 and retained against displacement by a screw 22 secured to the rod 20 and operating in a cutout portion 20b in the sleeve 20a. The sleeve 20a also carries a radially extending arm in which is supported a plurality of radially arranged and inwardly projecting pins 23, which arm is normally arranged at one side of an arc-shaped segment 24 adjustably supported upon a plate 25 attached to the back wall of the box.

The outer surface of the segment 24 is provided with a soft surface adapted to be scratched or marred by the pins 23 in the attempt of opening the box after breaking the seal 19. The sleeve 20a is rotated in the operation of turning the screw 18 by virtue of the engagement of a pin 25a on the screw with a notched portion 20c on the outer face of said sleeve. It will be understood that the rotation of the sleeve 20a is limited by the dimensions of the cut out portion 20b but the movement is sufficient to operate the pins 23 over the entire surface of the member 24. The surface of this member is visible through the transparent panel 15 as seen in Figs. 1 and 3 of the drawings.

It will be understood that the arm of the sleeve carrying the pins 23 will normally be at the right as seen in Fig. 1 of the drawings, so that in an attempt to release the screw 18, said arm will move to the left over the surface of the member 24, it being further understood that the ends of the pins 23 are normally in the plane of or below the plane of the outer surface of the member 24 so as to form grooves or ridges in said surface as indicated in Fig. 5 of the drawings.

Supported in connection with the back wall of the box 10 is a frame 26 of insulating material such as bakelite, hard rubber or fibre, and this frame constitutes a unit, including the mechanism supported or arranged thereon, which is detachable as a unit with respect to the box 10. The upper end of the frame 26 is reduced, and supported in connection with the sides thereof and on its front or outer face are two sets of spring terminals 27-27a, 28-28a. The circuit wires 29 and 29a which are adapted to extend to an electric meter or to any other electrical device through the pipe 11, are connected with the terminals 27a and 28a respectively as clearly seen in Fig. 2 of the drawings.

Slidably mounted on two guide pins 30 projecting from the outer face of the frame 26 is a cross arm 31 composed of insulating material, the outer ends of the pins 30 being headed to limit the outward movement of the arm 31, and springs 30a are arranged on the pins to normally move the arm 31 outwardly

to disengage switch bars 32 supported in connection with the ends of the arm 31 from the pairs of contacts 27-27a, 28-28a. The arm 31 and bars 32 constitute a switch device for controlling the electric circuit to the wires 29 and 29a.

The central portion of the arm 31 is offset inwardly to form a yoke-shaped portion 31a to the central part of which is attached a shaft 33 which projects outwardly through the aperture in the inwardly pressed portion 14a of the cover 14, and to which is secured an operating knob 34 by means of a screw 34a.

Secured to the inwardly pressed portion 14a of the cover are inner and outer sleeves 35 and 36 coupled together by screws 37, the latter operating in cam grooves 38 in the tubular extension 39 of the knob 34, the outer ends of said cam grooves having straight locking portions 38a, note Fig. 4, so as to retain the knob 34 in its innermost position as seen in Fig. 3 of the drawings, the springs 30a supporting said knob in extended position as seen in Fig. 4 of the drawings.

Rotatably mounted on the sleeve 36 adjacent the outer face of the cover 14 is a hand lever 40 which is provided on its outer face with a plurality of projecting members 41 adapted to engage inwardly projecting teeth on a ring 42 attached to the inner surface of the knob 34, when the knob is in the position shown in Fig. 3 so that in the upward movement of the lever 40 which projects beyond the periphery of the knob as seen in Fig. 1, said knob will be released and permitted to move into the position shown in Fig. 4 in a quick manner to prevent flashing or arcing in the operation of breaking the circuit through the respective pairs of terminals 27-27a, 28-28a in the movement of the bars 32 out of engagement therewith.

The frame 26 includes two outwardly projecting box-shaped members 43, both of which are of similar construction, and rotatably mounted in each of said projecting members and shafts 44 which set into recesses in the outer edges of the side walls of the casing 10 and are provided at their outer ends with knobs 45 by means of which said shafts may be rotated, the knobs being eight sided and alternate surfaces having arranged thereon the numerals 1 to 4 inclusive.

Secured to the shafts 44 within the box-shaped members 43 are fuse supporting drums 46 provided at equally spaced points about the periphery thereof with four longitudinal bores in which four fuses 47 are adapted to be supported, the fuses being placed in position by slidable engagement with the drums from either side thereof when one bore is exposed beyond the outer surface of the cover 14 and when the hoods 16 are raised into open position.

It will be seen upon a consideration of Figs. 2, 3 and 6 of the drawings, that the fuses are

exposed through the peripheral surface of the drums 46 and it will also be apparent that the terminal ends of said fuses open into annular recesses 48 formed in the opposite side walls of the drums 46 so as to permit the engagement of spring contacts 49 with said terminal ends as clearly seen in Fig. 6 of the drawings. Intermediate the fuses 47, the drums 46 are provided with outwardly extending rib-like projections 46a which act as dummies to take the place of the fuses to support the drums 46 in position with the fuses out of engagement with the contacts 49 as will be apparent.

15 It will be seen that the spring contacts 49 are U-shaped in form so as to firmly grip and engage opposite surfaces of the terminal ends of the fuses 47, one part of the contacts riding in the grooves 48 and the other part being arranged on the outer surfaces of the drums, the latter part having resilient properties, and the fuses are adapted to snap into these contacts as well as the enlarged portions 46a.

20 25 The contacts 49 are all of the same general construction, and those arranged adjacent the inner ends of the drums 46 include coupling plates and terminals 50 and 51 arranged in channel portions of the respective members 43, and with which circuit wires 52 and 53 from a suitable source passed into the casting 10 through the pipe 12 are coupled. In like manner, the contacts 49 arranged adjacent the outer ends of the drums 46 include 25 coupling plates or conductors 54 and 55 which extend to and are in circuit with the spring contacts 27 and 28 respectively as clearly seen in Fig. 2 of the drawings.

30 40 Pivotaly supported in connection with one of the members 43 as seen at 56, note Fig. 3, is a lock lever 57, one end of which includes spaced arms 58 arranged beneath the offset portion 31a of the arm 31 at opposite sides of the shaft 33, and the other end of said lever is arranged centrally of and between the members 43 and is provided with a U-shaped socket 59 in the recess of which the adjacent square ends of the shafts 44 are adapted to rest when the knob 34 is in the position 35 shown in Fig. 3, so as to prevent the rotation of the drums 46 when the circuit is completed through the terminals 27-27a, 28-28a. A spring 60 is provided to normally support the lever 57 in inoperative position when the knob is extended as seen in Fig. 4, or in other words, with the U-shaped end 59 out of engagement with the shafts 44.

45 The use and operation of my improved switch and fuse box will be readily understood from the foregoing description when taken in connection with the accompanying drawings and the following statement.

In the first place, the fuse drums 46 are filled with the fuses 47, and this result is accomplished when the knob 34 is in the posi-

tion shown in Fig. 4 and with the hoods 15 in raised position. Each bore or chamber in the drums 46 is brought into position externally of the cover 14 by the rotation of the knobs 45 and the fuse inserted until all four fuses are in position in each of said drums, after which one of the fuses of each drum is brought into position to engage the separate pairs of contacts 49 in the members 43, the numbered surfaces of the knobs 45 guiding the operator in this operation, after which and assuming that the wires 29-29a, 52 and 53 have been coupled with their respective terminals, the knob 34 is rotated by hand to move the switch bars 32 into engagement with the separate pairs of contacts 27-27a, 28-28a, thus placing the wires 52 and 53 in circuit with the wires 29-29a through the respective fuses in the drums 46.

45 Should one of the fuses burn out or become otherwise inoperative, the same may be replaced by first breaking the circuit in the operation of the switch which is accomplished by moving the lever 40 upwardly as hereinbefore stated, and the drum 46 having the inoperative fuse is rotated through its knob 45 to bring another fuse in position. At this time, if desired, the old inoperative fuse may be replaced by proceeding as in accordance with the original installation of the fuse.

50 With a structure of this type, it will be apparent that in addition to providing a storage for extra fuses, I provide means whereby a fuse may be replaced in any electric circuit in a quick, safe and practical manner.

55 It will also be understood that by providing a casing or box of the class disclosed, I also prevent tampering or interference with the main circuit wires coming from a source of supply and leading to the output, especially through a meter, means being provided for detecting unauthorized use or opening of the case. It will also be understood that the main mechanism of my improved switch and fuse unit may be insertable into and removed from the casing proper as a unit, thus facilitating repair or replacement of parts should any of the parts become inoperative.

60 While I have shown and described certain details of construction for carrying my invention into effect, it will be understood that I am not necessarily limited to these details, and various changes therein and modifications thereof may be made within the scope of the appended claims without departing from the spirit of my invention or sacrificing its advantages.

65 Having fully described my invention, what I claim as new and desire to secure by Letters Patent, is:—

disposed at the opposite end portions thereof adapted to open and close the circuit through said wires, tensional devices cooperating with the end portions of the bar to normally support the same in open circuit position, a knob arranged outwardly of the casing and in operative engagement with said bar, and means whereby the rotation of said knob in one direction will move said bar and switch blades into closed circuit position and retain the same in such position against the action of said tensional devices and whereby the rotation of the knob in the opposite direction will quickly release and move said bar and blades into open circuit position.

2. A switch device of the class described comprising a casing, means for admitting circuit feed and supply wires to the casing, a switch element within the casing and comprising an elongated bar having switch blades disposed at the opposite end portions thereof adapted to open and close the circuit through said wires, tensional devices cooperating with the end portions of the bar to normally support the same in open circuit position, a knob arranged outwardly of the casing and in operative engagement with said bar, means whereby the rotation of said knob in one direction will move said bar and switch blades into closed circuit position and retain the same in such position against the action of said tensional devices and whereby the rotation of the knob in the opposite direction will quickly release and move said bar and blades into open circuit position, and a lever cooperating with said knob in releasing the same.

3. A switch device of the class described comprising a casing, means for admitting circuit feed and supply wires to the casing, a switch element within the casing and comprising a bar having switch blades disposed at the end portions thereof adapted to open and close the circuit through said wires, tensional devices cooperating with the end portions of the bar to normally support the same in open circuit position, a knob arranged outwardly of the casing and in operative engagement with said bar, means whereby the rotation of said knob in one direction will move said bar and switch blades into closed circuit position and retain the same in such position against the action of said tensional devices and whereby the rotation of the knob in the opposite direction will quickly release and move said bar and blades into open circuit position, and means for sealing the casing and detecting unauthorized opening of the casing comprising a screw and a marking member actuated in the rotation of said screw and movable relatively to a sensitive surface.

4. A switch device of the class described comprising a casing, means for admitting circuit feed and supply wires to the casing,

a switch element within the casing and comprising a bar having switch blades disposed at the end portions thereof adapted to open and close the circuit through said wires, tensional devices cooperating with the end portions of the bar to normally support the same in open circuit position, a knob arranged outwardly of the casing and in operative engagement with said bar, means whereby the rotation of said knob in one direction will move said bar and switch blades into closed circuit position and retain the same in such position against the action of said tensional devices and whereby the rotation of the knob in the opposite direction will quickly release and move said bar and blades into open circuit position, means for sealing the casing and detecting unauthorized opening of the casing comprising a screw and a marking member actuated in the rotation of said screw and movable relatively to a sensitive surface, and a sealed element arranged outwardly of the casing and normally preventing the rotation of said screw.

5. A switch device of the class described comprising a casing, means for admitting circuit feed and supply wires to the casing, a switch element within the casing and comprising a bar having switch blades disposed at the end portions thereof adapted to open and close the circuit through said wires, tensional devices cooperating with the end portions of the bar to normally support the same in open circuit position, a knob arranged outwardly of the casing and in operative engagement with said bar, means whereby the rotation of said knob in one direction will move said bar and switch blades into closed circuit position and retain the same in such position against the action of said tensional devices and whereby the rotation of the knob in the opposite direction will quickly release and move said bar and blades into open circuit position, means for sealing the casing and detecting unauthorized opening of the casing comprising a screw and a marking member actuated in the rotation of said screw and movable relatively to a sensitive surface, a sealed element arranged outwardly of the casing and normally preventing the rotation of said screw, and a transparent panel in said casing rendering said sensitive surface visible when the casing is sealed.

6. A switch device of the class described comprising a casing, means for admitting circuit feed and supply wires to the casing, a switch element within the casing and comprising a bar having switch blades disposed at the end portions thereof adapted to open and close the circuit through said wires, tensional devices cooperating with the end portions of the bar to normally support the same in open circuit position, a knob arranged outwardly of the casing and in operative engagement with said bar, means whereby the rotation of said knob in one direction will move said bar and switch blades into closed circuit position and retain the same in such position against the action of said tensional devices and whereby the rotation of the knob in the opposite direction will quickly release and move said bar and blades into open circuit position, and means for sealing the casing and detecting unauthorized opening of the casing comprising a screw and a marking member actuated in the rotation of said screw and movable relatively to a sensitive surface.

- rotation of said knob in one direction will move said bar and switch blades into closed circuit position and retain the same in such position against the action of said tensional devices and whereby the rotation of the knob in the opposite direction will quickly release and move said bar and blades into open circuit position, two independently rotatable fuse supporting members mounted in said 10 casing, portions of said members being exposed through one wall of the casing, means exposed through the casing for rotating said members, and the peripheral surfaces of said members having bores exposed through said 15 surfaces and opposite sides of said members, fuses adapted to be assembled into said bores through one side thereof when exposed externally of the casing and retained in position by the cross sectional contour of the 20 bores.
7. A switch device of the class described comprising a casing, means for admitting circuit feed and supply wires to the casing, a switch element within the casing and comprising a bar having switch blades disposed at the end portions thereof adapted to open and close the circuit through said wires, tensional devices cooperating with the end portions of the bar to normally support the same 25 in open circuit position, a knob arranged outwardly of the casing and in operative engagement with said bar, means whereby the rotation of said knob in one direction will move said bar and switch blades into closed circuit position and retain the same in such 30 position against the action of said tensional devices and whereby the rotation of the knob in the opposite direction will quickly release and move said bar and blades into open circuit 35 position, two independently rotatable fuse supporting members mounted in said casing, portions of said members being exposed through one wall of the casing, means exposed through the casing for rotating said 40 members, the peripheral surfaces of said members having bores exposed through said surfaces and opposite sides of said members, fuses adapted to be assembled into said bores through one side thereof when exposed externally of the casing and retained in position by the cross sectional contour of the 45 bores, and means cooperating with the switch bar and said fuse supporting members for retaining said members against rotation 50 when the switch bar is in closed circuit position.
8. A circuit control of the class described comprising a casing, means whereby circuit feed and supply wires may be extended into 55 said casing, a switch element for controlling the circuit through said wires, fuse supporting members, the fuses of which control the circuit through said wires, said fuse supporting members comprising cylindrical bodies independently rotatable in the casing 60 and having longitudinal bores exposed through the side edges and outer peripheral surface of said members, the arrangement of said members in the casing being such as to expose externally of the casing at least one of said bores, fuse devices adapted to be placed in said bores from the exterior of the casing, and spring contacts arranged within the casing and in circuit with said wires and adapted to engage the terminal ends of one of the devices in each supporting member. 70
9. A circuit control of the class described comprising a casing, means whereby circuit feed and supply wires may be extended into said casing, a switch element for controlling the circuit through said wires, fuse supporting members, the fuses of which control the circuit through said wires, said fuse supporting members comprising cylindrical bodies 75 independently rotatable in the casing and having longitudinal bores exposed through the side edges and outer peripheral surfaces of said members, the arrangement of said members in the casing being such as to expose externally of the casing at least one of said bores, fuse devices adapted to be placed in said bores from the exterior of the casing, spring contacts arranged within the casing and in circuit with said wires and adapted to engage the terminal ends of one of the devices in each supporting member. 80
10. A circuit control of the class described comprising a casing, means whereby circuit feed and supply wires may be extended into said casing, a switch element for controlling the circuit through said wires, fuse supporting members, the fuses of which control the circuit through said wires, said fuse supporting members comprising cylindrical bodies 85 independently rotatable in the casing and having longitudinal bores exposed through the side edges and outer peripheral surfaces of said members, the arrangement of said members in the casing being such as to expose externally of the casing at least one of said bores, fuse devices adapted to be placed in said bores from the exterior of the casing, spring contacts arranged within the casing and in circuit with said wires and adapted to engage the terminal ends of one of the devices in each supporting member, and the side walls of said supporting members having grooves to receive parts of said spring contacts. 90
11. A circuit control of the class described comprising a casing, means whereby circuit feed and supply wires may be extended into said casing, a switch element for controlling the circuit through said wires, fuse supporting members, the fuses of which control the circuit through said wires, said fuse supporting members comprising cylindrical bodies 95 independently rotatable in the casing and having longitudinal bores exposed through the side edges and outer peripheral surface of said members, the arrangement of said members in the casing being such as to expose externally of the casing at least one of said bores, fuse devices adapted to be placed in said bores from the exterior of the casing, spring contacts arranged within the casing and in circuit with said wires and adapted to engage the terminal ends of one of the devices in each supporting member and hinged cover plates on said casing forming enclosures for said fuse supporting members. 100
12. A circuit control of the class described comprising a casing, means whereby circuit feed and supply wires may be extended into said casing, a switch element for controlling the circuit through said wires, fuse supporting members, the fuses of which control the circuit through said wires, said fuse supporting members comprising cylindrical bodies 105 independently rotatable in the casing and having longitudinal bores exposed through the side edges and outer peripheral surface of said members, the arrangement of said members in the casing being such as to expose externally of the casing at least one of said bores, fuse devices adapted to be placed in said bores from the exterior of the casing, spring contacts arranged within the casing and in circuit with said wires and adapted to engage the terminal ends of one of the devices in each supporting member and hinged cover plates on said casing forming enclosures for said fuse supporting members. 110
13. A circuit control of the class described comprising a casing, means whereby circuit feed and supply wires may be extended into said casing, a switch element for controlling the circuit through said wires, fuse supporting members, the fuses of which control the circuit through said wires, said fuse supporting members comprising cylindrical bodies 115 independently rotatable in the casing and having longitudinal bores exposed through the side edges and outer peripheral surface of said members, the arrangement of said members in the casing being such as to expose externally of the casing at least one of said bores, fuse devices adapted to be placed in said bores from the exterior of the casing, spring contacts arranged within the casing and in circuit with said wires and adapted to engage the terminal ends of one of the devices in each supporting member and hinged cover plates on said casing forming enclosures for said fuse supporting members. 120
14. A circuit control of the class described comprising a casing, means whereby circuit feed and supply wires may be extended into said casing, a switch element for controlling the circuit through said wires, fuse supporting members, the fuses of which control the circuit through said wires, said fuse supporting members comprising cylindrical bodies 125 independently rotatable in the casing and having longitudinal bores exposed through the side edges and outer peripheral surface of said members, the arrangement of said members in the casing being such as to expose externally of the casing at least one of said bores, fuse devices adapted to be placed in said bores from the exterior of the casing, spring contacts arranged within the casing and in circuit with said wires and adapted to engage the terminal ends of one of the devices in each supporting member and hinged cover plates on said casing forming enclosures for said fuse supporting members. 130

- independently rotatable in the casing and having longitudinal bores exposed through the side edges and outer peripheral surfaces of said members, the arrangement of said members in the casing being such as to expose externally of the casing at least one of said bores, fuse devices adapted to be placed in said bores from the exterior of the casing, spring contacts arranged within the casing and in circuit with said wires and adapted to engage the terminal ends of one of the devices in each supporting member, and a rotatable knob externally of the casing for moving said switch element into open and closed circuit positions.
12. A circuit control of the class described comprising a casing, means whereby circuit feed and supply wires may be extended into said casing, a switch element for controlling the circuit through said wires, fuse supporting members, the fuses of which control the circuit through said wires, said fuse supporting members comprising cylindrical bodies independently rotatable in the casing and having longitudinal bores exposed through the side edges and outer peripheral surface of said members, the arrangement of said members in the casing being such as to expose externally of the casing at least one of said bores, fuse devices adapted to be placed in said bores from the exterior of the casing, spring contacts arranged within the casing and in circuit with said wires and adapted to engage the terminal ends of one of the devices in each supporting member, and means cooperating with said switch element and said fuse supporting members for preventing the rotation of said members when said element is in closed circuit position.
13. In a circuit control device of the class described a fuse supporting member comprising a cylindrical body, means whereby said body may be rotated, a plurality of bores in the periphery of said body and opening through opposite sides thereof, fuses adapted to be mounted in said bores through either side wall of said body, spring contact devices in circuit with the wires to be controlled by one of the fuses of said member, and means whereby said fuses may engage the terminal ends of said contact devices.
14. In a circuit control device of the class described, a fuse supporting member comprising a cylindrical body, means whereby said body may be rotated, a plurality of bores in the periphery of said body and opening through opposite sides thereof, fuses adapted to be mounted in said bores through either side wall of said body, spring contact devices in circuit with the wires to be controlled by one of the fuses of said member, means whereby said fuses may engage the terminal ends of said contact devices, and said fuse supporting member being arranged in a casing in such manner as to expose at least one of the bores thereof externally of the casing to facilitate the replacement of the fuses externally of the casing.
15. In a circuit control device of the class described, a fuse supporting member comprising a cylindrical body, means whereby said body may be rotated, a plurality of bores in the periphery of said body and opening through opposite sides thereof, fuses adapted to be mounted in said bores through either side wall of said body, spring contact devices in circuit with the wires to be controlled by one of the fuses of said member, means whereby said fuses may engage the terminal ends of said contact devices, said fuse supporting member being arranged in a casing in such manner as to expose at least one of the bores thereof externally of the casing to facilitate the replacement of the fuses externally of the casing, and means movable with respect to said member for controlling the rotation thereof.
16. In a circuit control device of the class described, a fuse supporting member comprising a cylindrical body, a casing in which said body is rotated, a plurality of recesses spaced circumferentially of said body and opening outwardly through the periphery thereof, fuse elements arranged in said recesses and one or more of which are normally projecting through the casing, a contact in said casing and engaging one end of said fuse elements, and another contact engaging the other end portion of said fuse elements whereby the circuit of the wires leading to said contacts will be completed and controlled by one of the respective fuse elements in said body.
17. In a circuit control device of the class described, a fuse supporting member comprising a cylindrical body, a casing in which said body is rotated, a plurality of recesses spaced circumferentially of said body and opening outwardly through the periphery thereof, fuse elements arranged in said recesses and one or more of which are normally projecting through the casing, a contact in said casing and engaging one end of said fuse elements, another contact engaging the other end portion of said fuse elements whereby the circuit of the wires leading to said contacts will be completed and controlled by one of the respective fuse elements in said body, and one end portion of said body including a finger piece arranged outwardly of the casing and by means of which said body may be rotated with respect to said casing.
- In testimony that I claim the foregoing as my invention I have signed my name this 27th day of February 1929.
- CHARLES DRIEST.
